UNITED STATES PATENT OFFICE.

RUSSELL P. DUNMIRE, OF ERIE, PENNSYLVANIA, ASSIGNOR TO ERIE MALLEABLE IRON COMPANY, OF ERIE, PENNSYLVANIA, A CORPORATION OF PENNSYLVANIA.

CONDUIT BOX.

Application filed December 19, 1925. Serial No. 76,486.

This invention is designed to simplify conduit boxes, particularly such boxes as are used with threadless couplings. Features and details of the invention will appear 5 from the specification and claims.

The invention is illustrated in the accompanying drawings as follows:—

Fig. 1 shows a central section on the line 1—1 in Fig. 2.

Fig. 2 a section on the line 2—2 in Fig. 1.

Fig. 3 a perspective view of the locking shoulder bending tool.

Fig. 4 a detached view of the operating cam on the bending tool.

15 1 marks the body of the box, 2 a conduit-receiving extension, the extension having a tapered opening 3. A contractible sleeve 4 operates against the walls 3. It has an axial slit 5 and a guard shoulder 6. It is provided with the enamel penetrating ribs 7 adapted to engage an inserted conduit 8.

20 Tongues 9 are cast on the walls of the box which is ordinarily a malleable casting. The tongues initially are of such shape as to permit the insertion of the sleeve 4 into the conduit receiving opening. The conduit is inserted in the sleeve and the tongues 9 are bent forward and with the same operation the sleeve is forced into clamping engagement with the conduit.

25 Convenient means for accomplishing the bending of the tongue is provided by the shoulder bending tool. This is formed with a block 10 having a central slot 11 in which is arranged an eccentric 12. A handle 13 extends from the eccentric. The eccentric operates on a bolt 14, the cross head 15 extending from the bolt into position to engage the tongues 9. The opposite end of the block has projections 16 which are adapted to engage the base of the opposing tongues. By swinging the eccentric, the bolt 14 is forced outwardly forcing the tongues into

engagement with the rear of the sleeve forcing the sleeve into clamping engagement 45 with the conduit and at the same time seating the tongues in place against the sleeve as shown at the left of Fig. 1. Thus the entire assembling of the device is accomplished with a single movement of the tongue bending tool. If desired, a gasket 17 may be arranged at the front of the sleeve 4 and this is engaged by a flange 18 on the extension.

50 55 What I claim as new is:—

1. In a conduit box, the combination of a body having a conduit-receiving opening and an inwardly projecting bendable tongue extending from the body back of the opening, and a slitted contractible sleeve in the opening, the walls of said opening and sleeve having wedging surfaces contracting the sleeve with an endwise movement of the sleeve in the opening, and said tongue having an initial position permitting the insertion of the sleeve and in the opening and being bendable to permit of the forcing of the tongue into locking engagement with the sleeve in place in the opening. 60 65

2. In a conduit box, the combination of a body having a conduit-receiving opening and inwardly projecting bendable tongues extending from opposite sides of the body back of the opening; and a slitted contractible sleeve in the opening, the walls of said opening and the sleeve having wedging surfaces contracting the sleeve with an endwise movement of the sleeve in the opening, and said tongues having an initial position permitting the insertion of the sleeve in the 70 75 opening and being bendable to permit of the forcing of the tongues into locking engagement with the sleeve in place in the opening. 80

40 In testimony whereof I have hereunto set my hand.

RUSSELL P. DUNMIRE.
